LAUNDRY MACHINE

Ray C. Sandin, Northbrook, Ill., assignor to General Electric Company, a corporation of New York

Application December 31, 1952, Serial No. 22,953

Term of patent 14 years

(Cl. D49—1)

To all whom it may concern:

Be it known that I, Ray C. Sandin, a citizen of the United States, residing at Northbrook, in the county of Cook and State of Illinois, have invented a new, original, and ornamental Design for a Laundry Machine, of which the following is a specification, reference being had to the accompanying drawing, forming a part thereof:

Fig. 1 is a front perspective view of a laundry machine showing my new design.

Fig. 2 is a front view thereof with the lower body portion of said machine being broken away.

Fig. 3 is a fragmentary top plan view of the laundry machine, particularly illustrating the top surface of the back-splasher portion thereof.

Fig. 4 is a fragmentary sectional view thereof, taken on lines 4—4 of Fig. 2 and looking in the direction of the arrows.

The dominant features of the design reside in the portion shown in full lines.

I claim:

The ornamental design for a laundry machine, substantially as shown and described.

RAY C. SANDIN.
